United States Patent Office

Des. 178,604
Patented Aug. 28, 1956

178,604

BOX FOR SET OF GAGES

Herbert H. Heil, Rochester, N. Y.

Application April 15, 1955, Serial No. 35,537

Term of patent 14 years

(Cl. D58—12)

FIG. 1

FIG. 2

Fig. 1 is a perspective view of a box for a set of gages shown in open position and showing my new design.

Fig. 2 is a perspective view thereof, shown in closed position.

I claim:

The ornamental design for a box for a set of gages, substantially as shown.
